UNITED STATES PATENT OFFICE

ROBERT O. KIRCHHAN, OF MILWAUKEE, WISCONSIN

VALVE

Application filed March 9, 1928. Serial No. 280,310.

This invention relates to certain new and useful improvements in valves and refers more particularly to that type designed to be incorporated in the sewerage and drainage system of a building.

The primary object of this invention is to improve and simplify the construction of drain valves and to provide means for manually actuating the same.

Another object of this invention is to provide a drain valve of the character described having means for manually actuating the valve proper which means may be located at a remote point.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

The single figure is a side elevational view of a valve embodying my invention, parts thereof being broken away and in section to more clearly illustrate structural details.

Referring now more particularly to the accompanying drawing, in which like numerals designate like parts throughout the several views, 5 designates a casting forming the body of the valve, which is substantially inverted T shaped, the transverse portion or head of the T having its ends 6 and 7 provided with means for connection with a main sewer and a building drain, respectively. The main sewer is adapted to be connected with the outlet end 6 by a suitable pipe or conduit 8 and the inlet end 7 is adapted to be connected with the building drain through a suitable drain pipe 9.

The vertical portion 10 of the valve body terminates in a flange 11 to which a head or

cover member 12 is adapted to be secured by cap screws 13, a packing 14 being inserted in a recess formed in the under side of the cover member to seal the joint between the flange member and the cover. Positioned inwardly of the inlet end 7 is an apertured wall 15 which has a flanged sleeve secured to its inner side by cap screws 17 passed through the flange. The inner end of the sleeve 16 opposite its flanged end is tapered, as illustrated, with its longest wall at the bottom and forms a seat with which a valve 18 cooperates to close the passage between the outlet 6 and the inlet 7.

The valve 18 is pivotally mounted, as at 19, from an arm or projection 20 extended inwardly and upwardly from the upper portion of the sleeve flange and is provided with upstanding spaced lugs or ears 21 which are strengthened by webs 22. The outer ends of the lugs 21 are apertured to receive a pivot pin 23 to pivotally connect a link 24 therewith, the link being pivotally connected, as at 25, with a downwardly extending bifurcated portion 26 of a guide member 27. The pivot 25 is positioned medially of the ends of the link 24 and its end opposite its pivotal connection 23 is provided with a rounded portion 28 which abuts an arcuate wall 29 forming the inner wall of the vertical portion 10 of the body member.

The guide member 27 is longitudinally slidably mounted within an upwardly extending tube or pipe 30 threaded, at its lower end, in an aperture 31 formed in an upwardly extended portion of the cover member and having its upper end threaded to receive a substantially L shaped bracket member 32. Ribs or fins 33 extending radially from the guide member 27 guide the movement of the member within the pipe. The guide member 27 is connected with a manually operated handle member 34 by a connecting rod or tube 35 positioned within the pipe 30 and passing upwardly through the bracket member 32 to have its outermost end connected with the operating handle by a fork member 36 pivotally connected with the handle, as at 37. A stuffing gland 38 of any suitable construction seals the sliding joint between the operat-

ing rod 35 and the aperture in the bracket member 32 through which it extends.

An arm 39 extended laterally from the bracket member 32 pivotally mounts one end 40 of an upwardly extending connecting link 41 to the outer end 42 of which the operating handle 34 is pivoted, movement of the handle raising and lowering the rod 35 to open and close the valve. In closing, the end 28 of the link 24 abuts the arcuate portion 29 and downward pressure exerted on the link tends to move the link towards the inlet 7 and forces the valve 18 against the periphery of the sleeve 16, as will be readily apparent.

The bracket 32 is provided with an upwardly extending web or flange 43 having slotted projections 44 at each end thereof and the handle member is provided with a threaded eye bolt 45, the loop of which is passed around the handle and the threaded end being inserted through the slot of the extension 44 to have a wing nut 46 threaded thereon to secure the handle in either of its positions.

From the foregoing description, taken in connection with the accompanying drawing, it will be readily apparent to those skilled in the art to which an invention of the character described apertains, that I have provided a drain valve for preventing the backing up of a sewer into the house drain, which is positively operated by manual means, which means may be positioned remote from the valve.

What I claim as my invention is:

1. In a drain valve including a body member having an inlet and an outlet, a valve within the body member and adapted to either communicate or disconnect the inlet from the outlet, a link extended from the valve and having one end abutting an inner wall of the body member when the valve is in closed position, a cover member carried by the body member, a tube extended from the cover member, an operating rod positioned within the tube, means connecting one end of the rod with the link, said means forming a guide for the rod to maintain the same properly spaced from the walls of the tube, and means connected with the free end of the rod for actuating the rod to either of its positions.

2. In a drain valve including a substantially inverted T-shaped body member having the ends of its head adapted for connection with drain pipes, a sleeve member mounted within the body member adjacent one end thereof, the inner end of the sleeve member providing a valve seat, a valve engageable with the valve seat, means pivotally mounting the valve from the sleeve member, a cover member closing the open stem of the inverted T-shaped body member, and means for actuating the valve to and from closed position including a tube carried by the cover

member, a rod slidable in the tube, means connecting one end of the rod with the valve, and actuating means carried by the remote end of the tube for moving the rod to open and close the valve.

3. In a drain valve of the character described, a body member having opposed open ends adapted for connection with drain pipes, a flange formed on the body member adjacent one end, a sleeve member fixed to said flange, the inner face of said sleeve member forming a valve seat, a valve engageable with the seat to shut off communication between the open ends of the body member, means pivotally mounting the valve from the sleeve member, a cover member closing the open top of the body member, and means for moving the valve member to and from closed position including a tube extended from the cover member, a rod slidably mounted within the tube, a link pivotally connected with the inner end of the rod at a medial point, means pivotally connecting one end of the link with the valve whereby downward movement of the rod causes the free end of the link to abut the inner wall of the body member and close the valve on its seat, and actuating means carried by the remote end of the tube for moving the rod to open and close the valve.

4. In a drain valve including a body member having a pair of ports and an open top, a sleeve member mounted within the body member adjacent one of said ports and having a valve seat, a valve pivotally mounted from said sleeve member and engageable with said valve seat to shut off communication between the body member ports, a cover member closing the open top of the body member, means for actuating the valve to and from closed position including, a tube carried by the cover, a rod slidably in the tube, means connecting one end of the rod with the valve, and actuating means carried by the remote end of the tube for moving the rod to open and close the valve.

In testimony whereof I hereunto affix my signature.

ROBERT O. KIRCHHAN.
